CLAIM

The ornamental design for a training tennis racquet, as shown and described.

DESCRIPTION

FIG. 1 is a front elevational view of a training tennis racquet showing my new design;

FIG. 2 is a fragmentary left side elevational view of the handle portion thereof;

FIG. 3 is a fragmentary right side elevational view thereof;

FIG. 4 is a fragmentary rear elevational view of the handle portion thereof; and

FIG. 5 is an enlarged transverse sectional view taken along the line 5—5 of FIG. 1.

The essential features of my design reside in the indicia on the handle.

FIG. 2

FIG. 3

FIG. 4

FIG. 5
